UNITED STATES PATENT OFFICE.

JULIUS L. BORN, OF DETROIT, MICHIGAN.

GARBAGE-RECEPTACLE FOR SINKS.

1,225,308.

Specification of Letters Patent.

Patented May 8, 1917.

Application filed January 26, 1916. Serial No. 74,285.

To all whom it may concern:

Be it known that I, JULIUS L. BORN, a citizen of the United States, and residing at Detroit, in the county of Wayne and State 5 of Michigan, have invented a new and Improved Garbage-Receptacle for Sinks, of which the following is a specification.

The object of the present invention is to provide a detachable garbage receptacle 10 (preferably paper) together with an inexpensive support therefor whereby it may be mounted in an ordinary kitchen sink, and among its important features are the following: a receptacle formed of paper or the like 15 and means for detachably supporting it in one corner of the sink; a cover flap for the receptacle whereby the hand of the user may press upon and yet be prevented from contacting with the contents of the receptacle 20 when the latter is to be thrown away; receptacle supporting means including a wire arm having lateral projections that pass through perforations in the side of the receptacle, whereby the latter may be readily 25 secured in place or detached; and a paper receptacle adapted to fit the corner of a sink and so formed that it may be readily collapsed or flattened for transportation and storage. The invention further resides in 30 the details of construction shown, described and claimed.

In the drawings, Figure 1 is a fragmentary perspective view showing an embodiment of the invention that is particularly 35 adapted for use in a sink provided with a metal drain-board. Fig. 2 is a perspective view of the support shown in Fig. 1. Fig. 3 is a plan view thereof. Fig. 4 is a plan view of the blank from which the receptacle 40 is formed. Fig. 5 is a view, similar to Fig. 1, showing an embodiment of the invention adapted for use with a sink having a wooden drain-board. Fig. 6 is a similar view showing the same support applied to a sink having 45 no drain-board. Fig. 7 is a perspective view of the support shown in Figs. 5 and 6 before bending.

Like reference characters indicate like parts throughout the several views. 50 As best indicated in Fig. 4, the container is preferably formed from a paper blank (treated with paraffin or other moisture resisting substance) comprising the sector shaped body portion 1 and the side portions 55 2 and 3 that terminate, respectively, in the cover flap 4 and the edge flap 5. One of the

portions 2 or 3 is also provided with a gummed sealing flap 6. When bent as shown in Figs. 1, 5 and 6, a container is formed of substantially the shape of a 90° 60 segment of a cone, the sides 2 and 3 then being arranged at right angles to one another and secured together by the gummed flap 6, which is bent along the crease 8. After the flap 6 is gummed to the opposed 65 side portion 2 or 3, the body portion may be pressed inwardly along the bisecting crease 9 (Fig. 4), and the sides then collapsed upon each other by bending about their intersection 10 (Fig. 1), the cover flap 4 being flat 70 along the side 2 (Figs. 1 and 6), thus providing for very convenient shipping. The size and shape of the flap 4 is such that, when turned over the top of the receptacle, one hand of the user may grasp the lower 75 part of the latter and the other hand may be pressed down upon and yet not come into actual contact with the contents thereof. The receptacle may in this manner be very 80 conveniently carried from the sink and its 85 contents thrown, together with the receptacle itself, into the usual closed metal garbage receptacle or other receiver. The body and sides are preferably perforated as indicated at 12 to allow proper drainage. 85

The upper edges of the sides 2 and 3 are provided with perforations or slots 13, one near each end thereof; and, as shown in Figs. 1, 2 and 3, the receptacle may be supported on wire arms 15 and 16 that are 90 crimped at 18 to form projections which are adapted to extend through the corresponding perforations 13. From the intersecting point the arms are twisted together and extended downwardly to form a supporting 95 member 18' that terminates in a foot 19 which is adapted to rest directly on the bottom 20 of the usual sink. The sides 2 and 3 then conform to the sides 21 and 22 of the sink, the flap 4, when the sink is provided with a metal drain-board 23, being bent down along the corresponding side of the sink in the manner shown. 100

When the sink has a wooden drain-board 24 (Fig. 5) or when it has no drain-board 105 (Fig. 6), a support is formed by bending a wire in the manner indicated in Fig. 7. This support includes an arm 25 crimped to form projections 26 which correspond to the projections 18 heretofore described; from 110 the end of the arm the wire is looped in two preferably U-shaped ends 28 and 29, contin-

uous with each other. The portion 29 is welded or otherwise secured at 30 to the adjacent end of the arm 25; and from the welding point the wire is extended parallel to the arm to form an anchor portion 31 which may have its end looped at 32 and terminates in an upwardly extending projection 33. It will be observed that the outer end of the flap 4 is perforated at 34. When the receptacle is to be used in a sink having a wooden drain-board 24 (Fig. 5), the end 29 is bent down into the plane of the end 35 of the sink and the end 28 and anchor portion 31 are extended along the top of the drain-board, the loop 32 being engaged over a nail or the like 36. The receptacle is then hooked over the arm 25 (which is inclosed between the side 3 and the flap 5 in an obvious manner), and the flap 4 is turned out over the top of the drain-board until the projection 33 passes through the perforation 34. When the receptacle is filled the user places one hand against the bottom, then releases the flap 4 and bends it over upon the garbage. By continuing to press upon the cover the receptacle is gripped between the hands and may be detached from the supporting arm and thereafter thrown along with its contents into a more permanent receiver.

The same support is easily adapted to a sink having no drain-board (Fig. 6) by merely bending the end 28 down parallel to the end 29 so that the end 35 of the sink is inclosed between them. The flap 4 rests on the projecting anchor portion 31 and is hooked over the end 33.

In the embodiments shown in Figs. 5 and 6, the flaps 4 and 5 (and in that which appears in Fig. 1, the flap 5) cover and conceal the metal support for the most part and prevent corrosion.

It is clear that many changes may be made in the details of construction without departing from the spirit of my invention; for example, the edge of the flap 5 may be gummed to the side 3 to form a passage through which the wire 25 may be inserted. I do not, therefore, wish to be limited except as indicated by the subjoined claims.

I claim:—

1. In combination with a sink, a garbage receptacle support mounted in position to support a garbage receptacle therein, said support including an arm having a plurality of spaced, upwardly extending projections thereon, and a paper garbage receptacle having perforations in which the projections are received, whereby the receptacle may be readily secured on the arm or detached therefrom.
2. In combination with a sink, a garbage receptacle support mounted in position to support a garbage receptacle therein, said support including an arm having a plural-

ity of spaced upwardly extending projections thereon, and a paper garbage receptacle having perforations in which the projections are received, whereby the receptacle may be readily secured on the arm or detached therefrom, said receptacle having an open top and a flap arranged to be swung over the contents of the receptacle to prevent the hand of the user from being soiled thereby.

3. In combination with a sink and a drainboard therefor, a garbage receptacle conforming to one wall of the sink, said receptacle including a flap which is adapted to lie on top of the drainboard, and means for retaining the flap in the position stated.

4. In combination with a sink and a drainboard therefor, a paper garbage receptacle conforming to one wall of the sink, said receptacle including a flap which is adapted to lie on top of the drainboard, and to be swung over the top of the receptacle to prevent the hand of the user from being soiled by the contents thereof, and means for retaining the flap in the first named position, whereby the receptacle is prevented from moving away from the wall of the sink.

5. A garbage receptacle formed from a blank having a substantially sector shaped body portion, side portions along the radial edges of the body portion and arranged to be bent at right angles thereto, and a cover flap along one edge of one of the side portions, said cover portion being arranged to be swung about the said edge.

6. A garbage receptacle formed from a paper blank having a substantially sector shaped body portion, substantially triangular side portions along the edges of the body portion, a cover flap along one edge of one of the side portions, each of said side portions being arranged to be swung about the corresponding edge of the body portion, and the cover flap being arranged to be swung about the edge of the adjacent side portion.

7. A garbage receptacle formed from a paper blank having a substantially sector shaped body portion, substantially triangular side portions along the edges of the body portion, each of said side portions being arranged to be swung about the corresponding edge of the body portion to meet the other side portion, and a gummed flap along the meeting edge of one of the side portions whereby it may be secured to the other side portion, said body portion having a radial crease, whereby when the body portion is swung inwardly about the edges of the side portions and the latter are swung inwardly about their meeting edge, the receptacle is collapsed.

8. A garbage receptacle formed from a paper blank having a substantially sector shaped body portion, substantially triangu-

lar side portions along the edges of the body portion, each of said side portions being arranged to be swung about the corresponding edge of the body portion to meet the other side portion, and a gummed flap along the meeting edge of one of the side portions whereby it may be secured to the other side portion, the upper edge of one of the side portions being perforated, whereby the receptacle may be detachably secured on a support.

9. A garbage receptacle formed from a paper blank having a substantially sector shaped body portion, substantially triangular side portions along the edges of the body portion, each of said side portions being arranged to be swung about the corresponding edge of the body portion to meet the other side portion, a gummed flap along the meeting edge of one of the side portions whereby it may be secured to the other side portion, the upper edge of one of the side portions being perforated, whereby the receptacle may be detachably secured on a support, and a flap bendable about the perforated edge into parallel relation to the corresponding side portion.

10. A garbage receptacle formed from a paper blank having a substantially sector shaped body portion, substantially triangular side portions along the edges of the body portion, each of said side portions being arranged to be swung about the corresponding edge of the body portion to meet the other side portion, a gummed flap along the meeting edge of one of the side portions whereby it may be secured to the other side portion, a cover flap arranged to be swung about the upper edge of one of the side portions, said cover flap being perforated near its outer end for attachment to a support.

11. In combination with a sink, a wire garbage receptacle support including an arm mounted in position to support a garbage receptacle in the sink, said arm having spaced projections thereon, said support also including two end portions secured to the arm,

one of said end portions being adapted to be bent to conform to a surface of the sink, and a paper garbage receptacle carried on and detachable from the arm, said receptacle having perforations in which the projections on the arm are received.

12. In combination with a sink, a wire garbage receptacle support including an arm mounted in position to support a garbage receptacle in the sink, said arm having spaced projections thereon, said support also including two end portions secured to the arm, said end portions being adapted to be bent to conform to the edge of the sink, and a paper garbage receptacle carried on and detachable from the arm, said receptacle having perforations in which the projections on the arm are received.

13. In combination with a sink, a wire garbage receptacle support including an arm mounted in position to support a garbage receptacle in the sink, said arm having spaced projections thereon, said support also including two end portions secured to the arm, one of said end portions being adapted to be bent to conform to a surface of the sink, said support further including an anchor portion arranged to be secured to anchoring means located some distance from the edge of the sink, and a paper garbage receptacle carried on and detachable from the arm, said receptacle having perforations in which the projections on the arm are received.

14. In combination with a sink, a wire garbage receptacle support including an arm mounted in position to support a garbage receptacle therein, said support including a portion adapted to be bent to conform to a surface of the sink, said support also including an anchor portion arranged to be secured to anchoring means located some distance from the edge of the sink, and a paper garbage receptacle detachably supported on the arm.

In testimony whereof I sign this specification.

JULIUS L. BORN.
